COMBINATION HEDGE TRIMMER AND GRASS
CLIPPER

Edward M. Asbury, Pittsburgh, Pa.

Application April 23, 1956, Serial No. 41,150

Term of patent 14 years

I claim:

The ornamental design for a combination hedge trimmer and grass clipper, substantially as shown.
